UNITED STATES PATENT OFFICE.

CHARLES L. GOODRUM, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,412,734.

Specification of Letters Patent. Patented Apr. 11, 1922.

Application filed January 30, 1917. Serial No. 145,357.

To all whom it may concern:

Be it known that I, CHARLES L. GOODRUM, a citizen of the United States, residing at Brooklyn, in the county of Kings and State 5 of New York, have invented certain new and useful Improvements in Telephone Systems, of which the following is a full, clear, concise, and exact description.

This invention relates to telephone systems of that type employing machine switching.

The present arrangement has for its purpose the production of a telephone system which will be simple in construction, economical to manufacture, and effective in operation.

In step-by-step automatic telephone systems of the type generally employed, it is customary to use combinations of fast and 20 slow relays to control the setting and releasing of the automatic switches utilized in establishing a connection. It is the purpose of this invention to eliminate these combinations of fast and slow relays.

25 The main feature of this invention is the provision of a circuit arrangement in which the combination of fast and slow relays is dispensed with, and in which the operations normally controlled by these relays are controlled by the magnets employed in setting and releasing the automatic switches.

Other features of the invention will appear from the detail description and the claims.

35 Referring to the drawings, Figs. 1 and 2 represent diagrammatically a portion of a telephone system employing the present invention. Fig. 1 illustrates a non-numerical switch and a first selector with the operating 40 circuits of said switches. Fig. 2 illustrates a connector switch and its operating circuits.

It is believed that the operation of this system will best be understood by tracing a call through the various link circuits and 45 connecting switches.

When the subscriber, whose substation apparatus is indicated at A, removes his receiver from the switchhook, the line relay 74 attracts its armature. This completes a circuit which may be traced from grounded battery, left-hand winding of relay 74, outer armature and back contact of cut-off relay 50 75, armature and front contact of line relay 74, spring contact 76, left-hand armature and back contact of relay 77, relay 78 to ground.

55 74, spring contact 76, left-hand armature and back contact of relay 77, relay 78 to ground.

The relay 78 is energized and attracts its armatures. At its left-hand armature it completes a locking circuit which may be traced from ground, winding of relay 78, left-hand armature and front contact of relay 78, conductor 79, to grounded battery over the circuit previously described. At the right-hand armature of relay 78, ground is applied to segment 16 of the commutator 15 to stop the finder switch in one of its operations. This circuit may be traced from ground, right-hand armature and front contact of relay 78, conductor 5, to segment 16. At the right-hand armature and front contact of relay 78 a circuit is also completed 70 to energize the relay 80. This circuit may be traced from grounded battery, relay 80, left-hand armature and front contact of relay 78, to ground. The attraction of the left-hand armature of relay 80 closes a 75 break point in one of the operating circuits of the finder switch. This circuit may be traced from ground, right-hand armature and front contact of relay 78, left-hand armature and front contact of relay 80, to lead 80 6. At the right-hand armature of relay 80, the energizing circuit of relay 77, which controls the starter wire in the well-known manner, is completed. This circuit may be traced from grounded battery, winding of 85 relay 77, right-hand armature and front contact of relay 80, to ground.

As soon as ground is connected to lead 6, an operating circuit is completed for the primary magnet 7, which may be traced from 90 grounded battery, primary magnet 7, the armature of this magnet, side-switch wiper 8 in its first position, lead 6, left-hand armature and front contact of relay 80, right-hand armature and front contact of relay 78 to ground. An operating circuit in parallel with the last described circuit extends from grounded battery, primary magnet 7, escape magnet 12, side-switch wiper 13 in its first position, brush 14 of the commutator 15. The primary magnet 7, by interrupting its operating circuit, moves the brushes 9, 10 and 11 of the finder and commutator brush 14 until the brush 14 encounters the grounded segment 16 of the commutator, whereupon the escape magnet is energized and moves the side-switch wipers into position 2 in the well-known manner. 105

This prepares an operating circuit for the secondary magnet SM, which circuit may be 110

traced from grounded battery, secondary magnet SM, armature and back contact of this magnet, side-switch wiper 8 in its second position, lead 6 to ground. The secondary magnet SM continues to operate the brushes of the finder by interrupting its own circuit until the cut-off relay 75 of the calling line is energized over test brush 11, side-switch wiper 18 in its second position, 10 to ground.

The release magnet 19 herein employed is provided with an armature which carries holding dogs to hold the brush shaft in the position to which it has been advanced, as 15 clearly shown in the co-pending application of Messrs. C. L. Goodrum and J. A. Kropp, Serial No. 151,226 filed February 27, 1917. Simultaneously with the energization of primary magnet 7, the release magnet 19 20 is energized over a circuit which may be traced from grounded battery, release magnet 19, conductor 20, normally closed contact 21, side-switch wiper 22 in its first position, lead 6 to ground. The release 25 magnet 19 attracts its armature and thereby establishes a locking circuit which extends from grounded battery, magnet 19, its armature and front contact, side-switch wiper 22 in its first position, lead 6 to ground.

When the cut-off relay of the calling line is actuated, the energizing circuit of escape magnet 12 is interrupted by reason of the removal of ground potential from conductors 5 and 6. Escape magnet 12 thereupon deenergizes and moves the side-switch 35 wipers into their third position.

In the third position of side-switch wiper 22, an energizing circuit of release magnet 19 is completed which extends from ground- 40 ed battery, primary winding of release magnet 19, its armature and front contact, side-switch wiper 22, secondary winding of release magnet 19, conductor 23, armature and back contact of escape magnet 12 to ground. When the side-switch wipers 24^a and 24^b are moved into their third position, the calling line is extended to the first selector.

The primary magnet 25 of this first selector which magnet also performs the functions usually performed by the well-known line relay is energized over a circuit which may be traced from grounded battery, left-hand winding of primary magnet 25, side- 55 switch wiper 26 in its first position, lower side-of the line, side-switch wiper 24^b in its third position, finder brush 10, substation apparatus A, finder brush 9, side-switch wiper 24^a, upper side of the line, side-switch wiper 27, right-hand winding of primary magnet 25 to ground. Primary magnet 25 in energizing attracts its armature. This completes an energizing circuit for the release magnet 28 which in this system operates also 60 as the slow-releasing relay formerly used in

known systems. This energizing circuit may be traced from grounded battery, magnet 28, conductor 29, normally closed contact 30, conductor 31, armature and front contact of primary magnet 25 to ground. Release mag- 70 net 28 is energized and attracts its armatures. At its left-hand armature, it establishes a holding circuit for itself which extends from grounded battery, release magnet 28, its left-hand armature and front contact over 75 the circuit previously described. At its right-hand armature and front contact, release magnet 28 closes a break point in the energizing circuit of the secondary magnet 32, which magnet in the present system operates to perform the functions normally performed by the second slow-releasing relay of systems now in use. When the sending device at substation A is operated to send impulses corresponding to the first digit of 80 the desired number, the armature of primary magnet 25 vibrates to advance the switch and at its back contact completes an energizing circuit for the secondary magnet 32, which circuit may be traced from ground, 90 armature and back contact of primary magnet 25, conductor 33, right-hand armature and front contact of release magnet 28, secondary magnet 32 to grounded battery. Secondary magnet 32 attracts its armatures and at its right-hand armature and front contact completes an operating circuit for the escape magnet 34, which circuit may be traced from ground, front contact and right-hand armature of secondary magnet 32, side- 95 switch wiper 35 in its first position, escape magnet 34 to grounded battery. 100

At the termination of the first series of impulses, primary magnet 25 maintains its armature attracted for a relatively long in- 105 terval, and at the back contact and armature interrupts the energizing circuit of slow-releasing secondary magnet 32. The secondary magnet retracts its armatures and at its right armature and front contact in- 110 terrupts the operating circuit of escape magnet 34. In this instance, escape magnet 34 operates on its deenergization to move the side-switch wipers into their second position. An operating circuit for the escape 115 magnet 34 is now completed to test brush 36 over the following path: grounded battery, escape magnet 34, side-switch wiper 35 in its second position, conductor 37, test brush 36. In the second position of side-switch wiper 38, a self-interrupted operating circuit for secondary magnet 32 is completed from grounded battery, magnet 32, armature and back contact of this magnet, side- 120 switch wiper 38 in its second position, armature and back contact of escape magnet 34 to ground. The secondary magnet 32 continues to move the brushes 39, 40, and test brush 36 over the group of trunks until an 125 idle trunk is located. The idle condition 130

of the trunk will be indicated by ground potential on the test terminal 41 of the idle trunk. When test brush 36 of the selector engages this grounded test terminal, the escape magnet 34 is energized and in this instance, upon its energization, moves the side-switch wipers into their third position. It should here be noted that the escape magnet 34 in attracting its armature opens the operating circuit of secondary magnet 32, thus preventing overthrow of the switch if, for any reason, the side-switch wipers are not promptly moved into their third position.

When the side-switch wipers 26 and 27 are moved into their third position, the primary magnet 42 of the connector, which also performs the functions normally performed by the stepping relay, is energized. This energizing circuit extends from grounded battery, left-hand winding of primary magnet 42, side-switch wiper 43 in its first position, lower side of the line, brush 39, side-switch wipers 26 and 24^b, finder brush 10, substation apparatus A, finder brush 9, side-switch wiper 24^a, upper side of the line, side-switch wiper 27 in its third position, selector brush 40, side-switch wiper 55 in its first position, right-hand winding of primary magnet 42 to ground. Magnet 42 attracts its armature and thereby completes an energizing circuit for the slow operating release magnet 44, which in this system, also performs the functions normally performed by the second slow relay. The energizing circuit of magnet 44 extends from battery, magnet 44, normally closed contact 45, conductor 46, armature and front contact of magnet 42, side-switch wiper 47 in position 1, to ground. The magnet 44 attracts its armatures and at its left-hand armature completes a locking circuit for itself over the circuit previously described. When the calling device is operated to send the tens impulses, primary magnet 42 vibrates its armatures to advance the connector switch in its primary movement. At the first retraction of the armatures of magnet 42, an energizing circuit for escape magnet 48 is completed from grounded battery, winding of magnet 48, conductor 49, side-switch wiper 51 in its first position, right-hand front contact and armature of magnet 44, conductor 52, back contact and armature of magnet 42, to ground. Magnets 44 and 48 are adjusted to release slowly when their energizing circuits are interrupted. When, however, at the close of the tens series of impulses magnet 42 attracts its armatures for a relatively long interval the energizing circuit for escape magnet 48 is interrupted. Escape magnet 48 deenergizes and thereupon moves the side-switch wipers into their second position.

When the side-switch wipers 43 and 55 move into their second position, secondary

magnet 54 has its operating circuit completed from grounded battery, middle winding of this magnet, side-switch wiper 43 in its second position, over the path previously described for the operating circuit of the primary magnet, side-switch wiper 55 in its second position, right-hand winding of secondary magnet 54, to ground. The secondary magnet is energized and attracts its armature. In response to impulses from the sending device corresponding to the units digit of the desired number, secondary magnet 54 vibrates its armature. When the secondary magnet 54 attracts its armature, the release magnet will then be maintained energized over a circuit which may be traced from grounded battery, release magnet 44, its armature and front contact, conductor 56, side-switch wiper 73 in its second position, armature and front contact of secondary magnet 54, conductor 55^a, side-switch wiper 47 in its second position, to ground. Also in this position of the side-switch wipers, escape magnet 48 has its operating circuit completed over the following path: grounded battery, escape magnet 48, conductor 49, side-switch wiper 51, right-hand armature and front contact of release magnet 44, conductor 53, armature and back contact of secondary magnet 54, conductor 55^a, side-switch wiper 47 in its second position, to ground. It will be remembered that the release magnet 44 and the escape magnet 48 are slow to release, so that they do not deenergize during the momentary interruptions of their operating circuits when the armature of the secondary magnet 54 is vibrated.

When the test brush 57 of the connector is placed on the test terminal 59 of the desired line, if the desired line is idle, this condition will be indicated by raised potential at the test terminal. In this case the escape magnet 48 will be deenergized and will thereupon move the side-switch wipers into their third position. If, however, the desired line is busy, a timing device 60 is provided to prevent more than one connector seizing the desired line when it becomes idle, in case several connectors should be waiting to seize the terminals of this line.

This timing device consists of a constantly rotating shaft carrying discs provided with properly positioned insulating segments. With this timing device, the escape magnet 48 has an energizing circuit extending from grounded battery, escape magnet 48, left-hand winding of secondary magnet 54, armature and front contact of escape magnet 48, side-switch wiper 61 in its second position, brush 68, a conducting portion of the constantly rotating disc 63 and its shaft, through secondary winding of induction coil 62 to ground. A busy tone is imposed on the circuit just described, by means of the pri-

mary winding 73' of the induction coil and interrupter 72. The secondary magnet 54 acts as an induction coil and transmits the busy tone to the calling subscriber's receiver.

5 If the desired line becomes idle, the engagement of brush 68 with the insulated portion of the disc 63, causes escape magnet 48 to deenergize and move the side-switch wipers into their third position.

10 In this position of the side-switch wipers, ringing current will be applied to the desired line from ground, ringing generator 64, relay 65, side-switch wiper 66 in its third position, brush 69 of the connector, substitution apparatus B, brush 70 of the connector, side-switch wiper 67 to ground.

15 The relay 65 is marginal and does not operate until the called party removes his receiver, whereupon the energizing circuit 20 of escape magnet 48 which now extends from grounded battery, magnet 48, conductor 49, side-switch wiper 51 in its third position, armature and back contact of relay 65 to ground, is interrupted at the armature of 25 relay 65. The escape magnet upon deenergizing moves the side-switch wipers into their fourth or talking position.

20 It should be noted that the talking battery is supplied to the calling line through 30 the secondary magnet 54. This maintains the secondary magnet energized during the conversation. The talking battery of the called subscriber's line is supplied through the windings of the primary magnet 42.

35 The release of the switches utilized in establishing this connection is accomplished as follows: When the calling subscriber A replaces his receiver upon its switchhook, the secondary magnet 54, is deenergized. The 40 secondary magnet 54 thereupon retracts its armature and interrupts the energizing circuit of release magnet 44 which was previously maintained from grounded battery, magnet 44, left-hand armature and front 45 contact of this magnet, conductor 56, left-hand armature and front contact of magnet 42, front contact and armature of secondary magnet 54, conductor 55^a, side-switch wiper 47 in its fourth position to ground. The 50 release magnet thereupon retracts its armature and withdraws its holding pawls.

55 The release of the preceding selectors is accomplished when escape magnet 34 is again energized. This interrupts the energizing circuit of the release magnet 28, which circuit extends from battery, low-resistance winding and high-resistance winding of release magnet 28, side-switch wiper 38 in its third position, armature and back contact of escape 60 magnet 34 to ground. Release magnet 28, in retracting its armatures, withdraws the holding pawls and permits the switch to restore to normal. Escape magnet 34 which controls this release is energized over a circuit which 65 extends from grounded battery, escape mag-

net 34, side-switch wiper 35 in its third position, conductor 37, test brush 36, test terminal 41, conductor 71, right-hand armature and back contact of release magnet 44, conductor 53, armature and back contact of secondary 70 magnet 54, conductor 55^a, side-switch wiper 47 to ground. It will be remembered that release magnet of the finder switch was similarly controlled by the escape magnet 12 at its armature and back contact. An energizing circuit for the escape magnet 12, in parallel with the energizing circuit of escape magnet 34, may be traced from grounded battery, primary magnet 7, escape magnet 12, side-switch wiper 13 in its third position, 80 side-switch wiper 24 in its third position, side-switch wiper 35 in its third position, over the circuit previously described. The release magnet 19 is deenergized and its armature withdraws the holding pawls as previously described.

85 The release of the connector switch is also controlled by the called party. When the called party replaces his receiver, the primary magnet 42 retracts its armatures, and at its left-hand armature and front contact 90 interrupts the operating circuit of the release magnet 44. It will be remembered that in position 4 of side switch wiper 73, this 95 release circuit extends from grounded battery, release magnet 44, its left-hand armature and front contact, conductor 56, left-hand armature and front contact of relay 42, armature and front contact of relay 54, conductor 55, side-switch wiper 47 in position 100 4, to ground.

If the calling party abandons the call, while sending impulses corresponding to the first digit of the desired number, primary 105 magnet 25 will retract its armature and at its front contact and armature interrupts the energizing circuit of the release magnet 28, whereupon this magnet will restore the switch to its normal position. If the calling subscriber abandons the call before the impulses corresponding to the tens digits of the desired number are sent, primary magnet 42 will retract its armature and thereby interrupt the energizing circuit for the release 110 magnet 44, which circuit is maintained from grounded battery, release magnet 44, left-hand armature and front contact of this magnet, conductor 46, right-hand armature and front contact of primary magnet 42, side-switch wiper 47 in its first position to ground.

115 If the calling subscriber abandons the call before sending the units series of impulses, the operating circuit for the release magnet will be interrupted at the armature and front contact of magnet 54. This circuit, it will be remembered, extended from grounded battery, magnet 44, armature and front contact of magnet 44, conductor 56, side-switch wiper 73 in its second position, armature and front contact of magnet 54, conductor 55^a, 120 125 130

side-switch wiper 47 in its second position, to ground.

It will be understood that this disclosure is merely illustrative of applicant's improved system, and that the scope of the invention will be limited only by the appended claims.

What is claimed is:

1. In a telephone system, an incoming line, a plurality of outgoing lines, a switch for interconnecting said incoming line with any of said outgoing lines, a motor magnet for said switch, means for intermittently actuating said motor magnet, circuit-controlling switch, and an operating magnet therefor controlled by said motor magnet and arranged to be actuated at the close of a series of actuations of said motor magnet.

2. In an automatic telephone system, an automatic switch, telephone lines terminating therein in groups, a primary stepping magnet for moving said switch to select a group of said lines, a sender for intermittently actuating said primary magnet, a secondary stepping magnet for automatically moving said switch over the selected group to pick out an idle line therein, means for maintaining said secondary stepping magnet energized during the operation of said primary magnet, a circuit controlling switch having an operating magnet, and a circuit for said operating magnet controlled at a contact of said secondary stepping magnet.

3. In a telephone system, an incoming line, a plurality of outgoing lines, a switch for connecting said incoming line with any of said outgoing lines, a motor magnet for advancing said switch connected directly to said incoming line, armature contacts controlled by said motor magnet, a slow release magnet, and a circuit for said release magnet including contacts of said motor magnet to maintain said release magnet energized while the motor magnet is operating.

4. In a telephone system, an incoming line, a plurality of outgoing lines, a switch for connecting said incoming line with any of said outgoing lines, a motor magnet for advancing said switch connected directly to said incoming line, armature contacts controlled by said motor magnet, a release magnet, an escape magnet, and circuits for said release magnet controlled by said motor magnet and said escape magnet respectively.

5. In a telephone system, a switch, a primary motor magnet for said switch, armature contacts controlled by said magnet, a secondary motor magnet for said switch, a sender for intermittently operating said primary magnet, a circuit including said armature contacts for maintaining said secondary magnet energized during the operation of said primary magnet, a control switch, and a circuit for the magnet of said control switch closed by the operation of said secondary magnet.

6. In a telephone system, a switch, a primary motor magnet for operating said switch, armature contacts controlled by said magnet, a secondary motor magnet for operating said switch, an auxiliary circuit controlling switch, an operating magnet for said auxiliary switch, a circuit for said secondary magnet controlled at said contacts of said primary magnet, and a circuit for said auxiliary switch magnet controlled by said secondary magnet.

7. In a telephone system, a switch, a motor magnet for operating said switch, a slow magnet for releasing said switch, a side switch, armature contacts for said motor magnet, and a circuit for said release magnet including said armature contacts to maintain the release magnet energized in a certain position of said side switch.

8. In a telephone system, a switch, a motor magnet for operating said switch, a slow magnet for releasing said switch, a side switch, armature contacts for said motor magnet, and a circuit for said release magnet including said armature contacts to maintain the release magnet energized in a plurality of positions of said side switch.

9. In a telephone system, an incoming line, a plurality of outgoing lines, an automatic switch for connecting said incoming line with any of said outgoing lines, a motor magnet having windings connected directly to said incoming line for advancing said switch to the desired outgoing line, an electromagnet adopted to operate in case the called line is busy, a busy tone source, and a circuit including said source and a winding of said motor magnet closed by the operation of said electromagnet, said winding being inductively related to the windings in the incoming line.

10. In a telephone system, an incoming line, a plurality of outgoing lines, an automatic switch for connecting said incoming line with any of said outgoing lines, a motor magnet connected directly to said incoming line for advancing said switch to the desired outgoing line, an electromagnet adapted to operate in case the called line is busy, a busy tone source, a circuit including said source and a winding of said motor magnet closed by the operation of said electromagnet, said winding being inductively related to the windings in the incoming line, and means actuated by the called line becoming idle for disconnecting said tone source from the calling line and for causing said switch to signal the called line.

11. In a telephone system, an incoming line, a plurality of outgoing lines, an automatic switch for connecting said incoming line with any of said outgoing lines, a motor magnet connected directly to said incoming line for advancing said switch to

the desired outgoing line, a test relay, a circuit for operating the same if the called line is busy, and including a test contact of said called line, a busy tone source, a timing device, a locking circuit including said test relay, said source, a winding of said motor magnet, and said timing device closed upon the operation of said test relay, said winding being inductively related 10 to the winding in the incoming line, means actuated by the called line becoming idle

for opening the energizing circuit of said relay, and means controlled by the timing device for opening the locking circuit of said relay to disconnect said tone source, 15 and means for applying ringing current to the called line.

In witness whereof, I hereunto subscribe my name this 13th day of January A. D., 1917.

CHARLES L. GOODRUM.
